UNITED STATES PATENT OFFICE.

AXEL A. STROM, OF AUSTIN, ILLINOIS.

LIFTING-JACK.

SPECIFICATION forming part of Letters Patent No. 394,308, dated December 11, 1888.

Application filed July 21, 1888. Serial No. 280,640. (No model.)

To all whom it may concern:

Be it known that I, AXEL A. STROM, a citizen of the United States, residing at Austin, in the county of Cook and State of Illinois, 5 have invented a new and useful Improvement in Lifting-Jacks, of which the following is a specification.

My invention relates particularly to an improved construction of the friction-clutch portion 10 of the lifting-jack employed as the immediate means for raising the lifting-bar, when it is entitled the "lifting-clutch," being connected with and actuated from a lever fulcrumed on the standard and for retaining the 15 lifting-bar in its raised position, when it affords the retaining-clutch.

The lifting and retaining clutches in a lifting-jack may both involve substantially the same construction or may differ as to their 20 construction, and it is therefore within the spirit of my invention to employ in one lifting-jack my present improved form of clutch for one of the stated purposes and any other suitable form of clutch for the other purpose, 25 though both are shown to involve substantially the same construction in the accompanying drawings, in which—

Figure 1 shows in side elevation, with a portion 30 of the operating-lever broken away, a lifting-jack provided with my improved friction-clutch device. Fig. 2 shows the same as Fig. 1 in vertical section. Fig. 3 shows my improvement in section, both as a lifting and 35 as a retaining clutch in proper positions on a lifting-bar, the latter being indicated by dotted lines; and Fig. 4 shows a perspective view of the friction-clutch.

The objects of my improvement are to afford a construction of friction-clutch for lifting-jacks whereby longer surface-bearings 40 than have hitherto been had in clutches of somewhat similar construction shall be provided, thus permitting the gripping effect to be produced with slighter tipping and decreasing the rapidity of wear on the bearing parts.

A is a lifting-jack, of any suitable construction, to which my improved form of friction-clutch is adaptable, the construction of parts shown other than the clutches being in the 45 main that illustrated and described in Letters Patent of the United States, No. 388,156, granted me on the 21st day of August, 1888.

B is the hollow standard portion; C, the lifting-bar; D, the lever for actuating the lifting-clutch through a suitable link-connection *q*; and *r*, a guide-collar in the standard for the lifting-bar, the collar being merely a web connecting the two sides of the expanded portion of the standard and having a central opening for the lifting-bar, like the guide-collar in various well-known forms of lifting-jacks, wherein it performs the same function of a guide surrounding the lifting-bar toward the upper end of the standard.

The parts thus referred to not being new in 65 the present connection are not described more in detail.

E is the lifting-clutch, comprising a collar, *p*, preferably conforming in shape, at least as to its inner side, to that of the cross-section of the bar C, which passes through it, and having a handle projection, *o*, extending from one outer side, at which to connect it with the short end of the lever D, through the link-connection *q*. The inner side of the collar 75 adjacent to the outer side thereof from which the handle *o* extends affords the bearing-surface *n*, Fig. 3, of the clutch against one side of the lifting-bar, while the side of the collar directly opposite the surface *n* may be 80 open, as shown, or not, if preferred, a lip, *m*, extending from the under side of the collar and thus beyond the same, and affording outside the collar the bearing-surface for the opposite side of the bar.

By lowering the long arm of the lever D the clutch E is tipped, bringing the bearing-surface *n* and lip *m* against opposite sides of the bar and on different planes, whereby the bar is firmly gripped and caused to rise with whatever load may be upon it by the power exerted at the lever, and the construction affords long bearing-surfaces with the least quantity of material, thereby also requiring very slight tipping of the clutch to produce the desired 95 gripping effect and with comparatively little wear on the binding-surfaces.

The retaining-clutch E' involves in the collar *p'*, having the bearing-surface *n'* inside the collar, and lip *m'* at the opposite side of 100 the same, the same construction as the lifting-clutch, the difference between the two being that the projection *o'* is extended, as shown, farther than the part *o* to afford a handle suf-

ficiently long to permit its ready manipulation. The clutch E' is in reverse position on the bar with relation to the lifting-clutch, in order that the handle o' may extend at the 5 side of the jack where the operator stands, and thus be within ready access, and that the clutch may be fulcrumed on the seat l, formed at the base of the expanded upper portion of the standard B. As the clutch E' tends by 10 its own weight to tip upon its support, it normally grips the bar and prevents its falling when raised, the gripping effect being increased by the weight of the load on the bar. To release the retaining-clutch, pressure is exerted on the handle o', whereby the collar p' 15 is straightened and the gripping effect destroyed.

What I claim as new, and desire to secure by Letters Patent, is—

20 1. In a lifting-jack, the combination, with the standard B, lifting-bar C, and operating-lever D, of a lifting-clutch, E, comprising a collar, p, on the bar having a bearing-surface, n, on one inner side for the adjacent side of

the bar, a lip, m, integral with and extending 25 perpendicularly from its opposite side and affording a bearing-surface against the other side of the bar outside of the collar, a handle, o, extending from the collar, and a link, q, connecting the clutch E from the handle o 30 with the lever D, and a suitable retaining-clutch, substantially as described.

2. In a lifting-jack, the combination, with the standard B, lifting-bar C, and operating-lever D, of a suitable lifting-clutch and a retaining-clutch, E', comprising a collar, p', on the bar and supported on the standard, and having a bearing-surface, n', on one inner side for the adjacent side of the bar, a lip, m, integral with and extending from its opposite side and affording a bearing-surface 35 against the other side of the bar outside of the collar, and a handle, o', extending from the collar, substantially as described.

AXEL A. STROM.

In presence of—

M. J. BOWERS,

J. W. DYRENFORTH.
